UNITED STATES PATENT OFFICE

144,286

DESIGN FOR AN ATHLETIC SUPPORTER

Maurice B. Burston, Wethersfield, Conn.

Application August 30, 1945, Serial No. 121,744

Term of patent 7 years

(Cl. D3—17)

To all whom it may concern:

Be it known that I, Maurice B. Burston, a citizen of the United States, residing at Wethersfield, in the county of Hartford and State of Connecticut, have invented a new, original, and ornamental Design for an Athletic Supporter, of which the following is a specification, reference being had to the accompanying drawing, forming a part thereof.

Fig. 1 is a front view of an athletic supporter showing my new design;

Fig. 2 is a front view thereof showing the flap unbuttoned and in a lowered position; and

Fig. 3 is a plan view of the athletic supporter shown in Fig. 1. The entire flap of athletic supporter is made up of ribbed cloth with the ribs running in a vertical direction except for the oval insert in the crotch portion in which the ribs run in a horizontal direction, as shown in the drawing.

I claim:

The ornamental design for an athletic supporter, substantially as shown and described.

MAURICE B. BURSTON.
